TOY OIL DERRICKS AND PUMPERS

Joseph L. Bonanno, Madison, N. J., assignor to The Lionel Corporation, New York, N. Y., a corporation of New York

Application October 16, 1951, Serial No. 251,567

3 Claims. (Cl. 46—39)

The present invention relates to toy oil derricks and pumpers and is more particularly directed to such toys suitable for operation and toy railroad accessories to simulate the pumping of oil at an oil well.

The typical oil well pumper is used with a tall tower structure forming the oil derrick and employs a prime mover such as a diesel engine generating plant and an electric motor with reduction gears arranged to operate an oil pump.

According to the present invention the device is operated from a suitable low voltage source such as is available from a toy railroad transformer and an intermittently energized solenoid works the toy pump through a walking beam or rocker arm. This intermittent energization is controlled by a thermal circuit breaker. While the toy pump does not pump liquid, such action is here simulated by creating bubbles which ascend in a closed tube filled with liquid.

According to the preferred embodiment of the oil derrick and pumper, the thermal circuit controller, the solenoid with armature and the rocker arm are comprised in a preassembled unit which is secured to the base or platform from which the oil derrick rises. To further carry out the simulation of the full sized device, the thermal controller is covered by a plastic molding shaped to simulate the diesel power plant and the solenoid is covered by another plastic molding shaped to simulate the motor driven unit which operates an oil derrick pump.

Other and further objects will appear as the description proceeds.

The accompanying drawings show, for purposes of illustrating the present invention, one embodiment in which the invention may take form, it being understood that the drawings are illustrative of the invention rather than limiting the same.

In the drawings:

Figure 1 is a perspective view of the toy oil derrick and pumper;

Figure 2 is a perspective view of the preassembled rocker arm actuating unit;

Figures 3 and 4 are vertical sectional and inverted plan views, Figure 3 being taken on the line 3—3 of Figures 2 and 4;

Figures 5, 6 and 7 are vertical sectional views at a larger scale and taken on the lines 5—5, 6—6 and 7—7 respectively of Figure 4, to show the thermal circuit controller, the solenoid-rocker arm operator and the bubble tube; and

Figure 8 is a wiring diagram.

The entire toy is carried on a shallow rectangular, inverted sheet metal pan 10, the side walls 11 of which elevate the platform above the supporting surface so as to accommodate and conceal certain of the mechanism to be described. Near the left end of the base is the square tower 13 which carries hoisting tackle 14. These simulate the usual oil derrick. The tower is made of sheet metal and the lower corners are secured to the base by twisted prongs 15.

2

To the right of the tower, as shown in the drawings, the base carries a preassembled operating unit. All operating parts of this operating unit are carried on a relatively heavy sheet metal mounting plate 16 of general T shape as shown from Figure 2. The inner or left end of plate 16 carries a square, relatively low tower 17 provided with a horizontal shaft 18 on which is mounted a walking beam or rocker arm 19 made of a plastic molding. The tower 17 is secured in place by bent lugs 20.

To the right of the tower 20, a vertical solenoid coil 21 is secured to the plate 16 by a magnetizable frame 22 having twisted lugs 22' passing through the plate. This coil receives a plunger type armature 23 which projects down through a hole 24 in the top plate 16. The lower end 25 of the armature is secured to the lower end of a link 26, which extends up through holes 27, 27 in the plate 16 and is secured at its upper end 28 to the rocker arm. The weight distribution of the rocker arm and armature is such that the right-hand end of the rocker arm is normally lowered in the full line position of the drawings.

The right hand end of the plate 16 has a relatively large opening 29 which is covered by an insulating plate 30, secured in place by twisted ears 31 (Fig. 5). The insulating plate 30 supports one end of a bimetal warp element 32 whose free end is opposite an adjustable fixed contact 33. The warp element 32 is provided with a resistance heater coil 34 grounded to it and connected at its other end to a binding post 35 carried by the insulating plate.

The mounting for the adjustable contact 33 is connected by a wire 36 to the solenoid coil 21 having its other end grounded to the plate 16. The return binding post is shown at 37. When current is supplied these parts, the solenoid coil is energized and the rocker arm lifted. Soon the heater coil has caused the warp element to open the circuit. This deenergizes the solenoid and the warp element cools to reestablish the circuit. The frequency of the operation is controlled by the adjustment of the fixed contact 33.

The mounting plate 16 is secured to the platform 12 by twisted ears 38. To accommodate the tower lugs 20, the solenoid frame lugs 22', the armature 23 and link 26, the platform has a relatively large hole 39 under the left end of the plate 16. To the right, the platform has a relatively large hole 40 which accommodates the insulating plate 30 and binding posts 35 and 37.

The warp element and adjacent wiring are covered and concealed by a plastic molding 41 shaped to simulate a diesel electric power plant and secured in place on the plate 16 by screws 42. The solenoid 21, but not the link 26, is covered by another plastic molding 43 to simulate the electric motor and housing about the speed reducing mechanism. The cover 43 is held in place by friction clips 44 carried on depending studs 45. These covers protect the parts and enhance the play value of the toy.

Under the derrick tower the device is provided with devices to simulate the oil handling devices used with derricks in the oil industries. To carry out this illusion and relate it to the rocker arm, the base 10, as shown at the left of Figures 1, 3 and 4 and in Figure 7, has a plastic body 50 simulating the upper part of the pump mechanism and this is associated with a plunger 51 connected by a chain 52 with the rocker arm 19 so as to be moved up and down thereby. The plastic body is secured in place by friction clips 53, one carried on a stud 54, the other on a rod 55 adapted to be swung about and appear like a discharge pipe. The body also carries a transparent tube 56 to which is secured a plastic body 57 simulating the overhead piping.

The tube 56 is partly filled with methylene chloride and the usual granules 56' so that bubbles may be caused

to rise through the lighted liquid in the tube by a lamp bulb 58 which lights the tube and heats the bottom of the tube. The lamp is carried in a socket 59 which can be swung down as indicated in Figure 7, and is parallel with the solenoid circuit so that the bubbling continues while the pumping operation of the toy is going on.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A toy oil derrick comprising a base, an oil pump simulating body carried by the base and carrying a vertically movable pump plunger, a toy tower above the pump body, a mounting plate secured to the base to one side of the tower, a relatively low tower carried by the mounting plate, a solenoid coil carried by the mounting plate and having a vertically movable armature, a rocker arm carried by the low tower and connected at one end to the pump plunger and toward the other end to the armature, the weight of the armature acting to lift the pump plunger, a circuit closer having a fixed contact connected to the armature and a thermally operated movable contact having a heater coil in series, and an insulating support for the circuit closer carried by the mounting plate.

2. An operating unit for a toy oil derrick, comprising a sheet metal plate carrying at one end a rocker arm supporting tower and at the other end an electrically heated, warp element and circuit closer controlled by the warp element, and intermediate the ends a vertical solenoid coil above the plate and connected to the circuit

closer, a rocker arm pivoted on the tower and having one end extending over the top of the solenoid, a plunger type armature in the solenoid and a link connecting the bottom of the armature and the rocker arm to lower the said end 5 of the rocker arm by gravity and lift it when the solenoid coil is energized.

3. In a toy oil derrick, in combination, a base including a flat platform and depending elements elevating the base above a table or other flat support, a toy oil pump simulating device carried by the base, and a toy pumper including a metal plate mounted on top of the platform, a plate carried rocker arm supporting tower, a rocker arm pivoted on the tower, a solenoid carrying a plunger type armature protruding through the plate and through an aperture in the platform, a link connecting the bottom of the armature and the rocker arm, an insulating plate carried by the metal plate above an aperture therein, said plate aperture being above an aperture in the platform, a warp element carried by the insulating plate above 10 the same and carrying a heater coil in series with the warp element, an adjustable fixed contact against which the warp element normally bears and projecting down through both apertures to be accessible for adjustment under the base, and a wire connecting the fixed contact 15 with the solenoid coil.
